UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

DRAFT RIGGING.

Application filed December 30, 1921. Serial No. 525,874.

To all whom it may concern:

Be it known that I, DONALD S. BARROWS, a citizen of the United States, residing at Rochester, in the county of Monroe and 5 State of New York, have invented certain new and useful Improvements in Draft Rigging; and I do hereby declare the following to be a full, clear, and exact description of the invention, such as will enable others 10 skilled in the art to which it appertains to make and use the same.

The invention relates to draft rigging for railway cars and more particularly to a combined backstop and center filler casting 15 designed to be secured to the car center sills so as to transmit thereto and to the car underframe, the buffing shocks to which said casting is subjected in service.

The principal object of my invention, 20 generally stated, is to provide a combined yoke stop and center filler casting which may be effectively used with railway cars in which the center line of draft is below the longitudinal center line of the center or 25 draft sills.

Another object of the invention is to produce a backstop of great strength per unit 30 of weight, which is easy to manufacture and inexpensive to apply to car underframes, and in which the various webs and flanges are arranged to receive and distribute, without distortion, the enormous shocks or blows to which the casting is subjected in actual use.

To this end, the principal feature of my 35 invention, generally considered, consists in constructing a backstop with side walls which are preferably adapted to overlie and be secured to the webs of the adjacent car sills, and in providing said walls with inwardly converging portions adjacent the forward ends thereof, said portions being united by an end wall or web forming an 40 abutment for the movable part of the draft rigging, a longitudinal upright web extending rearwardly from said end walls and 45 transversely extending, downwardly inclined webs uniting each side wall to said upright web, said inclined webs also being united to 50 the said end wall.

Another feature of my invention consists in forming a backstop with end walls, one of which forms an abutment for a movable part of the draft rigging, said walls being

integrally connected to the side walls at 55 points spaced from the upper and lower portions of the latter, and in providing a plurality of transversely extending webs uniting said side walls, one of said webs being adapted to connect the said end walls, 60 the other web being vertically spaced therefrom.

Still another feature of my invention consists in providing a backstop with side and end walls integrally connected, one of said 65 end walls forming an abutment for a movable member of the draft rigging, an upright web extending between and uniting said end walls adjacent the central portions thereof, and a transversely extending web connected 70 to said upright web and to said side walls and spaced from the adjacent lower edges of said end walls.

There are other features of my invention 75 relating to form and details of construction, as will be hereinafter apparent from a more detailed description of the preferred embodiment of my invention which has been illustrated in the accompanying drawings, wherein

Figure 1 is a top plan view of my combined backstop and center filler casting, the abutting rear end of the draft yoke being shown in dotted lines.

Figure 2 is a central longitudinal vertical 85 sectional view of the construction shown in Figure 1.

Figure 3 is a transverse sectional view taken on line 3—3 of Figure 2, the direction of view being indicated by the arrows adjacent the ends of said section line.

Figure 4 is a rear elevational view of the casting, sections of the center or draft sills being indicated by dotted lines.

In the drawings, the numeral 1 designates 95 the combined back stop and center filler casting which is designed to cooperate with the draft rigging and to provide the center filler member of the ordinary type of built-up bolster. The casting 1 is adapted to fit between the webs of the center or draft sills 2 and to be rigidly attached thereto in any suitable manner. For convenience, I have illustrated my attachment in connection with the channel sills 2 having the 100 flanges 3 thereof turned inwardly, as clearly shown in Figure 4.

The front face or wall 4 of the casting 1

is adapted to engage the inner end of a yoke 5 to limit the inward movement thereof and to act as an abutment for transmitting to the car sills, through features hereinafter apparent, the buffing forces or blows transmitted to the casting by means of said yoke.

The casting 1, as here illustrated, is of substantial box shape and comprises, in addition to the front or outer wall 4, side walls 6, 6, a rear end wall 7, an intermediate wall 8, and a floor or base member 9. Adjacent their forward ends and intermediate the upper and lower edges thereof, the side walls 6, 6 are provided with inwardly converging portions 10 for connecting the side walls to the front wall 4. These portions 10, which, for convenience have been described as converging portions of the side walls, might also be described as divergent portions of the end wall 4.

The end walls 4 and 7 are preferably braced by a plurality of longitudinally extending upright ribs or flanges 11, 11 and 12, the latter being arranged on the center line of the casting. In order to reinforce and strengthen the casting against lateral strains, I provide each side wall 6 with an inwardly extending, downwardly sloping web 13 the adjacent edges of said webs being preferably integrally connected to the central upright web 12, as clearly shown in Figure 3. These webs 13 also extend from end wall to end wall and therefore materially strengthen the casting in a longitudinal direction.

The central web 12 and the intermediate wall 8 preferably converge at a convenient point into the open-ended cylindrical column 14 to form the thimble for the center pin or king bolt (not shown). It will be understood, of course, that this center thimble opens through the base or floor plate 9, as clearly shown in Figures 1 and 2.

The web 12 extends the full height of the end walls 4 and 7, both above and below the transversely extending webs 13, and is preferably downwardly extended below the lower edges of the said end walls and integrally connected to the base or floor plate 9 of the casting. The ribs 11 preferably extend above the upper faces of the flanges or webs 13 and are connected to the intermediate wall 8. Intermediate the wall 8 and the front face 4 of the casting, and below the webs 13, I preferably provide further reinforcing ribs 15 which are arranged for convenience, in alignment with the corresponding ribs 11.

The side walls 6 are provided with a plurality of rivet receiving openings 16 through which the rivets or other securing means, for connecting the casting to the sills, are adapted to extend, and in order to provide sufficient room to permit the driving of the rivets, which are adjacent the ribs 11, I

reduce the height of these ribs at their intermediate portions so as to provide ample clearance.

The intermediate wall 8 is preferably provided with inclined portions 17 which extend the full height of the side walls 6 and further reinforce the same against buckling under strains imposed upon the casting through the base or floor plate 9.

The base plate 9 is preferably provided adjacent its side edges with inclined portions 18 which overlie and conform to the adjacent flanges 3 of the center lines. The side walls are preferably extended in rear of the rear wall 7 and may be connected to this rear wall by triangular reinforcements 19. These reinforcements are, for convenience, formed in parallel planes to the webs 13.

It will be observed that the end walls 4 and 7 are spaced at their lower edges from the base or floor plate 9. By this construction I avoid all necessity for perforating the webs 13 since access to the rivet openings 16 may be had from both the front and rear ends of the casting. In this connection it might be pointed out that by arranging the webs 13 at an angle to the horizontal, I not only reinforce the end walls substantially along the center line thereof, but am enabled to provide an additional row of rivet openings in line with the intersection of the webs 13 and 12 but spaced from the marginal edges of the webs 13.

A combined backstop and center filler casting formed as here described is advantageous in that it presents to buffing shocks or blows a section of substantially I-beam form whose walls are disposed so as to resist most effectively these shocks and blows and to transmit these blows from the buffing face to the various structural members of the casting, without distortion or deformation. By arranging the transverse webs at an angle, I provide a symmetrical casting in relation to the rivet openings and thus prevent turning moments upon the rivets, that is the rivets by which the casting is secured to the sills, are subjected to shearing strains alone. It will also be apparent that by means of the internal ribs and flanges the casting hereinbefore described is so reinforced that all stresses to which it may be subjected in service, are amply resisted by sufficient sections of metal so economically arranged that the casting, while possessing great strength, is comparatively light in weight, and is moreover a simple casting both to mold and cast.

I claim:

1. A stop casting for railway draft rigging comprising spaced side walls, end walls integrally connected thereto, one of said last named walls being adapted to engage a movable element of the draft rigging, and means for reinforcing said last named wall, said

means including an upright flange extending substantially the full width of said last named wall and below the same for connecting the same to the base plate of said casting at a point substantially in vertical alignment with said end wall.

2. A stop casting for railway draft rigging comprising spaced side walls, an end wall, portions of said side walls being extended inwardly from the vertical planes thereof for connecting said side walls to said end wall, and means for reinforcing said end wall, said means comprising an upright web and a plurality of transversely extending downwardly sloping webs uniting said side walls to said web.

3. A stop casting for railway draft rigging comprising spaced side walls, a base plate connected to the lower edge thereof, an end wall connected to said side walls intermediate the ends thereof, and additional means for uniting said side walls comprising a plurality of downwardly inclined laterally extending webs and an intermediate upright web, said last named web being connected to said first named webs, said webs being adapted to brace said end wall.

4. A stop casting for railway draft rigging, comprising spaced side walls, an end wall connected thereto by integral inwardly extending portions of said side walls, a base plate connected to said side walls and vertically spaced from said end wall, said base plate extending forwardly to a point substantially in vertical alignment with the end wall, and means for connecting said base plate to said end wall.

5. A stop casting for railway draft rig-

ging comprising spaced side walls, a base plate, and end walls, and means for connecting said side and end walls above said base plate, said means including a pair of longitudinally extending downwardly converging webs, intersecting substantially in alignment with the longitudinal axis of said casting.

6. A stop casting for railway draft rigging comprising a box-like structure having end walls, spaced side walls, a base or floor plate connecting said side walls, downwardly inclined laterally extending webs adapted to connect said side and end walls, and a plurality of upright webs reinforcing said walls and said first named webs.

7. A stop casting for railway draft rigging comprising a front wall formed with diverging side portions, a rear wall, side walls extending above and below said end walls, a base plate connecting said side walls and spaced vertically from said end walls, and an upright web extending from said base plate to said points adjacent the upper edges of said end walls.

8. A stop casting for railway draft rigging comprising a pair of spaced side walls, end walls connected thereto, one of said end walls being adapted to engage a movable element of the draft rigging, and means for reinforcing said last named wall, said means comprising a plurality of spaced upright webs and a pair of transversely extending downwardly inclined webs connected to said end wall adjacent the central portion thereof.

In testimony whereof I affix my signature.
DONALD S. BARROWS.
